UNITED STATES PATENT OFFICE.

CARL S. ALLEN, OF CINCINNATI, OHIO.

OVERALLS.

1,410,541.

Specification of Letters Patent. Patented Mar. 28, 1922.

Application filed December 15, 1919. Serial No. 344,842.

To all whom it may concern:

Be it known that I, CARL S. ALLEN, a citizen of the United States of America, and a resident of Cincinnati, in the county of 5 Hamilton and State of Ohio, have invented a new and useful Improvement in Overalls, of which the following is a specification.

Heretofore the suspenders attached to 10 overalls have consisted of a like material attached to the middle section of the belt or waist band of the overalls. To accomplish this requires that the waist band or 15 belt be attached to the overalls, that then the suspenders be attached to said belt and then the suspenders must be sewed to one another at their intersection. Also before attaching, the suspenders must be bound or hemmed, constituting another necessary operation.

20 The object of my invention is to simplify the construction of overalls having suspenders attached to them, and to eliminate several of the operations now necessary to 25 complete such overalls.

In the accompanying drawings:

Fig. 1, is a rear elevation of my improved overalls having suspenders attached.

Fig. 2, is a fragmental perspective view 30 showing the relation of the suspenders to one another and to the overalls at the point of intersection of the suspenders.

Fig. 3, is a fragmental elevation showing 35 the intersection of the suspenders and the adjacent area.

Fig. 4, is a sectional view taken on line X—X of Fig. 3, and upon an enlarged scale.

40 My improvement comprises overalls having the rear edges inclined upward from the hip portions and terminating in a point, and two suspenders having a constant width throughout, attached to the upper edge of the rear portion of the overall, one end of 45 one suspender beginning at one hip of the garment and one end of the other suspender beginning at the other hip of the garment, then each extending along the upper edges of the rear portion of the overall until the

suspenders intersect one another. Beyond 50 this intersection the suspenders function as ordinary suspenders on the ordinary overalls.

The steps of forming the suspenders and of attaching them to the overalls, are as 55 follows:

The upper edge 1 of the overall is left 60 unfinished as shown at 1 on Fig. 4. The 65 suspenders 2 and 3 are made of two strips 4 and 5. Edges 6 and 7 of suspender 2 are 70 inturned and secured together by a line of stitching 8. The other edges of the suspender 75 are then inturned, the suspender is fitted over the edge 1 of the overalls 9 and a line of stitching 10 is passed through the inturned edges and the material of the overalls. Then suspender 3 is attached. Suspender 3 is constructed the same way as in suspender 2 except in that the two strips comprising suspender 2 pass between or 80 separate the two strips 4 and 5 comprising suspender 3 at the intersection of the 85 suspenders. The lines of stitching 8 and 10, binding strips 4 and 5 into suspender 3 also pass through strips 4 and 5 constituting suspender 2 at this point of intersection. Buttons 11 are attached to the suspenders.

Having thus described my invention, what I claim is:

Overall having a V shaped upper edge 80 of the back portion left unfinished, two binding strips each formed of two strips of material with their edges inturned, the aforesaid unfinished edge being inserted between the strips, one of said binding strips 85 passing between the strips forming the other of said binding strips, both binding strips extending beyond such mentioned point of intersection, lines of stitching passing through the inturned edges and through 90 said inserted portion of the overalls and the stitching in the second mentioned binding strip passing through the first mentioned binding strip at their intersection.

In witness whereof, I have hereunto subscribed my name this 12th day of December, 1919.

CARL S. ALLEN.
